UNITED STATES PATENT OFFICE

JOHN S. McCALLUM, OF GOLDFIELD, IOWA

ROAD MAINTENANCE MACHINE

Application filed December 3, 1928. Serial No. 322,336.

This invention relates to a device for maintaining roads in condition.

An object of the invention is the provision of a device including a wheel supporting frame adapted to be drawn over a roadbed in any approved manner and carrying an auxiliary frame which has universal connections with the main frame, a plow support being adjustably positioned transversely of 10 the main frame.

A further object of the invention is the provision of a road maintenance machine in which a main frame is supported by wheels, an auxiliary frame being connected 15 by a universal joint above and to the main frame, a ring supporting a plow having a greater diameter than the width of the main frame and adjustably positioned for varying the position of the plow, means being inter- 20 posed between the adjusting mechanism for the plow and the ring to compensate for movement in the plow due to the variation in the surface of the roadbed.

With the preceding and other objects and 25 advantages in mind, the invention consists in the novel combination of elements, constructions, arrangement of parts, and operations to be hereinafter specifically referred to, claimed and illustrated in the accompanying drawings, wherein:

Figure 1 is a plan view of a device constructed in accordance with the principles of my invention,

Figure 2 is a longitudinal side view of 35 the device,

Figure 3 is a vertical section showing the connection between the main frame and the auxiliary frame,

Figure 4 is a fragmentary view in perspective of a ring which supports the maintenance plow,

Figure 5 is a front end view in elevation of the device,

Figure 6 is a vertical section of a compensating device interposed between the adjusting mechanism and the plow,

Figure 7 is a transverse vertical section taken along the line 7—7 of Figure 1.

Figure 8 is a fragmentary view in elevation of a rear frame, and

Figure 9 is a perspective view of a detail of construction.

Referring more particularly to the drawings, 10 and 11 designate, respectively, the rear and front frames of the device. 55

Brace bars 12 extend inwardly from the rear frame 10 and are connected to a bar 13 secured to the I-beams 14 forming part of the structure of the auxiliary frame.

Brace bars 12 are connected at points adjacent the outer edges of the rear frame 10 and are inclined inwardly towards each other. Brace bars 15 are secured at points to the bottom of the rear frame 10 and extend upwardly and are connected, respectively, to the beams 14 of the auxiliary frame. 60

An axle 16 is secured to the rear frame 10 and is provided with supporting wheels 17.

A transverse bar 18 is secured to the under- 70 faces of the I-beams 14 and brace bars 19 are connected with the front frame 11 and to the underside of the bars 18, at points beneath the I-beams 14.

Curved beams 20 have their opposite ends secured to the opposite ends of the beams 75 14 and are braced intermediate their ends by standards 21. Brace bars 22 and 23 extend diagonally across the auxiliary frame and are connected at their opposite ends to the stems 21. 80

Diagonally disposed brace bars 24 are secured to the top of the rear frame 10 and to the underside of an end bar 25 which has its opposite ends connected to the rear ends of the I-beams 14. A transverse bar 26 is 85 secured to the front end of the I-beams 14.

Shafts 30 and 31 are mounted in bearings 32 in the front frame 11 and extend downwardly and each shaft is provided with an axle 33 on which is mounted a wheel 34. A 90

shaft 35 is mounted in bearings in the front frame 11 to which is rigidly connected a draw bar 36. When the draw bar is rocked in opposite directions and in a horizontal 95 plane the shaft 35 will be rocked, thereby rocking a gear 37 which is secured to a shaft 36. This gear meshes with a rack 38 secured to a sliding bar 39. A rack 40 at one end of the bar 39 meshes with a gear 41 which is rigidly secured to a shaft 30. A gear 42, 100

rigid with the shaft 31, meshes with a rack 43 likewise secured to the sliding bar 39 so that when the gear 37 is rocked and the rack 8 reciprocates racks 40 and 43 thereby causing rotation, respectively, of the gears 41 and 42. Rocking of the last-mentioned gears controls the steering of the wheels 34.

To facilitate the sliding movement of the bar 39, rollers 44 are carried by links 45 and 10 engage the bar 39.

A ring 50 which has a diameter greater than the width of the frame is supported below the auxiliary frame by means of cylinders 51 and piston rods 52. Each cylinder 15 has a pair of perforated ears 53 which receive a pin 54 carried by an ear 55. It will be noted that the ears 55 are located at diametrically opposite points on the ring 50. Each cylinder has a chamber 56 in which is 20 mounted a spring 57 having one end in engagement with the inner end of a hollow piston 58. The other end of the spring rests upon a shoulder 59 at the bottom of the chamber 56. A disk 60 is secured to a rod 61 and is normally disposed within the hollow piston 58 adjacent closed end 62 of said piston. The lower end of the rod 61 is threaded at 63 into the bottom of the cylinder 51. The upper end of the cylinder is provided 30 with slots 64 to receive the end of a bolt 65 which is secured in the hollow piston 58. The upper end of the hollow piston is secured, as shown at 66, to a pin 67, projecting from a gear 68 mounted for rotation on an axle 69.

35 The shaft 70 is mounted for rotation on the auxiliary frame and has a worm 71 in mesh with a worm gear 68. A crank 72 projecting beyond the front frame 11 is adapted to be rotated for causing rotation of the worm 40 and gear 68. It will be noted that the cylinders 51, together with the corresponding elements just described are located at opposite sides of the device and each is adjusted by its respective crank 72 or 72^a.

45 The cylinder 56 is filled with a liquid such as oil and to the level indicated at 73 so that the liquid extends into a hollow piston 58. The closed end 62 of the piston 58 is provided with passages 74 through which 50 the liquid may pass from the chamber 56 to the hollow piston. Flap valves 75 control the passages 74. The disk 60 is of slightly less diameter than the diameter of the hollow piston 58 so that liquid may pass around 55 the piston 60 and enter the hollow piston 58.

A pair of bars 80 are secured at their forward ends to the frame 11 and extend rearwardly over the ring 50 and have their rear ends pivoted at 81 to bars 82 which in turn 60 have their rear ends slidably mounted in slots 83 of the rear frame. A bar 84 has its opposite ends secured to the ring 50 at points adjacent the ears 55. A bar 86 is secured to the bars 80 as shown in Figure 7 and a pin 65 87 forms a pivotal connection between the

bar 84 and the bar 86 so that the ring 50 may be tilted slightly from a horizontal plane to opposite sides of the horizontal frame and forming with said horizontal plane an acute angle, the pin 87 having a universal connection with the bar 84.

A plow 88 is hingedly connected, at 89, to an arcuately-shaped member 90 which has its upper end secured to the ring 50. Brace bars 91 extend from the member 90 to points 75 at the rear portion of the ring 50 for aiding in bracing the arcuately-shaped member 90 which supports the plow 88. The plow is curved and inclined at an angle to a vertical plane passing centrally and transversely of 80 the frame. A link 92 is provided with a plurality of perforations 93 adapted to receive a bolt 94 carried by the member 90 whereby the inclination of the plow 88 may be varied 85 as desired.

The upper opposite corners of the front and rear frames 10 and 11 are provided with upstanding posts 95 carrying balls 96 which are received within sockets 97 formed of pairs of plates 98 and 99. These sockets are riveted 90 at 100 to the transverse bars 25 and 26.

The front ends of the bars 80 are secured to a plate 121 and this plate is provided with an opening which will loosely receive the shaft 35. The free end of the plate is located 95 between the bearing 120 secured to the front end frame 11 and a collar 123 rigidly secured to the lower end of the shaft 35. Ears 122 project forwardly from the collar 123 and these ears carry a bolt 124 upon which the 100 tongue 36 is pivotally mounted.

An opening in the plate 121 where it is received by the shaft 35 is sufficiently large and the collar 123 is spaced a sufficient distance from the bearing 122 to permit a slight 105 rocking of the plate 121.

It will be seen by this construction that the ring 50 may be tilted slightly to the horizontal due to the pivotal connection between the bars 80 and 82, the sliding connection of the bars 82 in the openings in the rear end frame 10 and the loose mounting of the plate 121 on the shaft 35.

It is important that the ring 50 be held as rigidly as possible so that the plow may not readily oscillate during operation so that the plow will be maintained in a substantially rigid engagement with the roadbed in order to accomplish the best results.

The operation of my device is as follows: The cranks 72 and 72^a are adjusted in order to properly position the plow 88 with respect to the roadbed as the device is drawn over the roadbed and the plow 88 strikes an obstruction the pressure exerted against the blade will tend to elevate the plow against the action of the spring 57 in the cylinder 56. However, the pressure is of such a nature that it may be overcome to prevent breakage 130

of the plow or any of the parts connected to the plow.

- When it is desired to tilt the plow transversely of the roadbed and at an angle to the horizontal the cranks 72 may be operated in reverse direction for causing elevation of one end of the plow while lowering the other. Since the ring 50 is supported upon the pin 86, said pin will act as a pivot for the ring.
- 10 When the plow 88 is moved upwardly the rods 80 are likewise moved upwardly and due to the pivotal connection at 81 with the rods 82 the rods 80 may be elevated with the ring 50. At this time the rods 82 slide through the bars 83 in the rear frame 10. The pivotal connections between the rods 80 and the front frame 11 also provide for the oscillation of the said rods.

It will be noted that a main frame is provided and an auxiliary frame is mounted upon the main frame by ball and socket connections thereby providing a certain amount of play between the main frame and the auxiliary frame. The auxiliary frame has an over-head trussed arrangement for reinforcing the auxiliary frame, the trussed section being connected to the longitudinally disposed I beams 14 at the opposite end of the trusses 20 and having a reinforced connection between the highest points of the trusses and the longitudinal beams 14, thus the main frame is capable of adjusting itself to any uneven portions of a road bed.

35 The ring 50 may not only be partially rotated, but may be tilted at an angle to the horizontal for varying the positions of the plow 88. The cylinder 51, piston 52 and the mechanism within the cylinder and piston will tend to maintain the ring 50 and plow 40 88 in their adjusted position.

I claim:

A road maintenance machine comprising a frame, wheels supporting the frame, a ring, a plow secured to the ring and disposed transversely of the frame, rods connecting the ring with one end of the frame, the other end of the frame having passages, rods having the outer ends received within the passages to provide a sliding connection for the rods with said end of the frame, the last mentioned rods being pivotally connected with the inner ends of the last-mentioned rods, and means for adjustably supporting the ring from the frame.

55 JOHN S. McCALLUM.
